(57) **CLAIM**

The ornamental design for a hair drier, as shown and described.

DESCRIPTION

Fig. 1.1 is a perspective view of the hair drier according to an embodiment of the present invention;

Fig. 1.2 is a front view of the hair drier of Fig. 1.1;

Fig. 1.3 is a rear view of the hair drier of Fig. 1.1;

Fig. 1.4 is a left-side view of the hair drier of Fig. 1.1;

Fig. 1.5 is a right-side view of the hair drier of Fig. 1.1;

Fig. 1.6 is a top of the hair drier of Fig. 1.1;

Fig. 1.7 is a bottom view of the hair drier of Fig. 1.1;

Fig. 1.8 is a perspective lower front view of the hair drier of Fig. 1.1;

Fig. 1.9 is a perspective lower rear view of the hair drier of Fig. 1.1; and

Fig. 1.10 is a perspective rear top view of the hair drier of Fig. 1.1.
